UNITED STATES PATENT OFFICE.

DAVID F. CRAWFORD AND ANTON K. KUSEBAUCH, OF PITTSBURGH, PENNSYLVANIA,
ASSIGNORS TO LOCOMOTIVE STOKER CO., OF PITTSBURGH, PENNSYLVANIA, A COR-
PORATION OF PENNSYLVANIA.

LOCOMOTIVE DRAFT APPLIANCE.

1,356,809.

Specification of Letters Patent. Patented Oct. 26, 1920.

Application filed March 10, 1919. Serial No. 281,798.

To all whom it may concern:

Be it known that we, DAVID F. CRAWFORD and ANTON K. KUSEBAUCH, citizens of the United States, residing at Pittsburgh, in the county of Allegheny and State of Pennsylvania, have invented certain new and useful Improvements in Locomotive Draft Appliances, of which the following is a specification.

10 This invention relates to locomotive draft appliances and particularly to that type embodying a blower fan and a turbine or other motor means for operating the fan.

One of the chief objects of our invention 15 resides in the provision of a novel arrangement of draft appliance, with the motor means located exteriorly of the smoke box and the conduit for supplying exhaust steam for operating the motor extending through 20 the smoke box.

Among the other objects of the invention are the provision of improved means for supporting the motor and the driving shaft; the provision of improved means for protecting the shaft bearings from the heat in 25 the smoke box; the utilization of a by-pass conduit for by-passing steam around the motor, as a means for supporting the shaft bearings and also as a means for subjecting 30 the bearings to a cooling bath of exhaust steam; and, in general the provision of a simple and economical arrangement of the various elements constituting the draft appliance.

35 We accomplish the foregoing, together with such other objects as may hereinafter appear, by means of a structure which we have illustrated in preferred form in the accompanying drawings, wherein—

40 Figure 1 is a longitudinal section through a locomotive smoke box showing the application of our improved draft appliance thereto; Fig. 2 is a partial end elevation of a locomotive equipped with our improved 45 draft appliance; Fig. 3 is a longitudinal section, partially broken away, through the shaft bearings and the means for conducting steam thereto, drawn on an enlarged scale; Fig. 4 is a section taken on the line 50 IV—IV of Fig. 3; and Fig. 5 is a section taken on the line V—V of Fig. 4.

Referring now particularly to Figs. 1 and

2, the smoke box is indicated at A and the draft appliance consists of a blower fan 7 located within the smoke box, a motor 8, 55 preferably of the steam turbine type and located exteriorly of the smoke box, and a driving shaft 9 coupled to the turbine shaft 9^a and extending into the smoke box, said shaft being supported in a manner to be 60 hereinafter described. The blower fan operates in the usual manner drawing the products of combustion from the fire box through the flues and discharging the steam 65 into the smoke box, the cinders being caught 65 by a series of baffles B. The steam turbine 8 also operates in the usual manner and the details of the internal mechanism thereof form no part of the present invention.

The housing of the turbine is provided 70 with a base portion 10 adapted to be bolted or otherwise secured to a pair of brackets 11 which are in turn secured to a portion of the adjacent structure, preferably the smoke box, to accomplish which we extend the 75 brackets rearwardly into the interior of the smoke box as indicated in Fig. 1. Exhaust steam is supplied to the interior of the turbine by a pipe or conduit 12 in the manner hereinafter described, and the steam, after 80 passing through the turbine, is discharged into the smoke box through the outlet 13.

The location of the steam turbine on the exterior of the smoke box, in addition to rendering the turbine more accessible for 85 inspection and repair and the draft appliance more easy to assemble, is to be preferred to an inside location where the mechanism would be subjected to the high temperature found within the smoke box, but 90 this arrangement involves extending the length of the shaft 9 and to adequately support this shaft we prefer to provide it with two spaced bearings 13 and 14, respectively 95 located near the ends of the shaft. The bearings are respectively housed in the limbs or branches 15 and 16 of a conduit 17 into which exhaust steam from the cylinders is admitted. Adjacent to its lower end conduit 17 is provided with a lateral branch 18 to which the pipe 12 is coupled and intermediate the limbs 15 and 16 and the branch 18, the conduit 17 is provided with a valve 100 mechanism, such as a butterfly valve 19, by

means of which the volume of steam passing through the lateral branch 18 and conduit 12 to the steam turbine may be controlled, thus governing the speed of rotation of the fan and thereby regulating the amount of draft to suit any operating conditions. If the valve 19 be wide open a relatively small quantity of steam will pass through the turbine, such quantity increasing with the shifting of the valve toward full closed position. The steam not passing through the lateral outlet 18 discharges upwardly through the conduit 17 and passes around the bearings 13 and 14, thereby cooling and protecting the same from the action of the relatively hotter products of combustion passing through the smoke box and extending their life. In order to facilitate assemblage the conduit 17 is preferably made in two halves, flanged as at 20, so that they may be bolted together.

The detail arrangement of the bearings in the by-pass conduit is shown in Figs. 4 and 5, from inspection of which it will be seen that the bearings have flanges 22 adapted to be secured to pedestals 23 formed in the interior of the lower half of the conduit. We prefer to drive the shaft 9 from the shaft 9^a of the turbine through the medium of a clutch mechanism 21 for the reason that assemblage of the draft appliance parts is facilitated and for the further reason that the arrangement divides the apparatus into a blower fan unit and a steam turbine unit, one advantage of which is that binding of the shafts is prevented.

It will be seen from the foregoing that we have provided an effective means for supporting the blower fan shaft and for protecting the bearings thereof, so that the life of the apparatus will be greatly extended. Binding between the parts is also eliminated, and the location of the conduit 12 within the smoke box tends toward efficiency in operation of the turbine because the exhaust steam does not lose its heat so rapidly as it otherwise would if the conduit were arranged entirely externally of the smoke box. The supporting of the turbine from the lower portion of the smoke box, at a point adjacent the point of support of the conduit 17, is also advantageous as this reduces the liability of relative shifting between the blower fan unit and turbine.

In order to insure the flow of some cooling steam to the fan shaft bearings under all running conditions, the valve 19 is given a loose fit or otherwise constructed so as to permit such flow even when the valve is closed.

We claim:—

1. A locomotive draft appliance comprising in combination means for producing a draft, an engine for driving the same operated by exhaust steam from the cylinders,

means for conveying exhaust steam thereto, a driving shaft, bearing means for said shaft, and independent means for subjecting said bearing means to a bath of exhaust steam.

2. A locomotive draft appliance comprising in combination rotary means for creating a draft, a motor, a driving shaft for operating said rotary means, spaced bearing means for said shaft, and independent means for subjecting each of said bearing means to a bath of exhaust steam.

3. A locomotive draft appliance comprising in combination a blower, a motor, a driving shaft, spaced bearing means for said shaft and independent means for subjecting each of the said bearing means to a bath of exhaust steam.

4. A locomotive draft appliance comprising in combination a blower in the smoke box, a motor, a shaft having spaced bearing means located in the smoke box, and independent means for subjecting each of said bearing means to a path of exhaust steam.

5. A locomotive draft appliance comprising in combination a blower in the smoke box, a motor arranged exteriorly of the box, a shaft for driving the blower having bearing means in the box, and means for subjecting said bearing means to a bath of exhaust steam.

6. A locomotive draft appliance comprising in combination a blower in the smoke box, a steam motor for driving the same, a shaft having bearing means in the box, means for supplying the motor with exhaust steam and a by-pass for the steam, said bearing means being located in the path of flow of by-passed steam.

7. A locomotive draft appliance comprising in combination a blower, a motor, a shaft, spaced bearings for said shaft, and independent steam conduits in which said bearings are mounted.

8. A locomotive draft appliance comprising in combination a blower, a motor, a shaft, spaced bearings for said shaft, a conduit for delivering exhaust steam to said motor, and a by-passing conduit in which said bearings are mounted.

9. A locomotive draft appliance comprising in combination a blower within the smoke box, a motor outside the box, a shaft, and supporting means for said parts comprising bearing means and a housing therefor mounted in the smoke box, said housing serving as a conduit for exhaust steam.

10. A locomotive draft appliance comprising in combination a blower within the smoke box, a motor outside the box, a shaft, and supporting means for said parts comprising bearing means and a branched conduit one member of which is coupled to the motor and the other of which supports the bearing means.

11. A locomotive draft appliance comprising in combination a blower within the smoke box, a motor outside the box, a shaft, and supporting means for said parts comprising bearing means and a branched conduit one member of which is coupled to the motor and the other of which supports the

bearing means, and valve means controlling the flow of steam through the said members of the conduit.

In testimony whereof we have hereunto signed our names.

DAVID F. CRAWFORD.
ANTON K. KUSEBAUCH.
